UNITED STATES PATENT OFFICE.

CLARENCE T. EVANS, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,243,722.

Specification of Letters Patent. Patented Oct. 23, 1917.

Application filed April 10, 1914. Serial No. 831,034.

To all whom it may concern:

Be it known that I, CLARENCE T. EVANS, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 5 a part of this specification.

This invention relates to improvements in electric switches.

It has among its objects to provide a power-operated switch with means to prevent accidental operation thereof while released.

Various other objects and advantages of the invention will hereinafter appear in connection with the embodiment of the invention illustrated in the accompanying drawing and now to be described.

In the drawing,

Figure 1 is a front elevation of the switch with a part thereof broken away and

Fig. 2 is a side elevation of the switch.

The switch as illustrated, includes stationary main and arcing contacts 1-2, operating contacts 3-4, a magnet 5 for operating the latter contacts and a device 30 for locking the contacts 3-4 out of engagement with contacts 1-2 when the magnet is deenergized.

The magnet 5 is mounted in a suitable magnetic frame 7 and has a magnetic core 8 projecting slightly beyond the outer end thereof. The contacts 3-4 are mounted upon a magnetic member 9 pivoted to the magnet frame, as at 10, and constituting an armature for the magnet 5. The arrangement is such that when the magnet 5 is energized it attracts its armature 9 to move the contacts 3-4 into engagement with the contacts 1-2, whereas the armature gravitates away from the magnet when deenergized to 45 separate said contacts. Further, a spring 11 interposed between the carrier of the contact 3 and the armature 9 serves, among other purposes, to give the armature 9 an outward impulse or kick-off when the magnet 50 net is deenergized.

The locking device 6 comprises an arm pivoted at one end to a suitable supporting post 12. This arm projects between the magnet 5 and its armature 9 and carries a

pin 13 projecting toward said armature. 55 The arrangement is such that the arm 6 may be raised and lowered to respectively move the pin 13 into and out of the path of the contact 4. Further, the parts are so arranged that when the pin is in the former 60 position it positively prevents sufficient inward movement of the armature to effect engagement of the contacts, whereas movement of said pin to the latter position relieves the armature of such restraint.

The operation of the arm 6 is entirely automatic and controlled by the magnet 5. It is provided with a spring 14 for normally holding the same in raised position and is constructed wholly or in part of magnetic material to be attracted and drawn downwardly against the action of the spring 14 by said magnet when energized. As illustrated, the arm 6 is so disposed as to be drawn against the core 8 and is provided at 75 its point of contact with a non-magnetic part 15 to effect a quick release thereof when the magnet is deenergized. Also as illustrated, the arm 6 is provided with a non-magnetic lug 16 engaging a part of the magnet frame 80 to limit the upward movement of said arm and to maintain its magnetic part out of engagement with said frame.

The operation of the switch as a whole is as follows: With the parts positioned as illustrated in Fig. 2, the magnet, when energized, attracts both the arm 6 and armature 9 and by the attraction of the former unlocks the latter. Thus the armature 9 moves inwardly to effect engagement of the contacts.

Deenergization of the magnet in turn effects the release of both the armature 9 and the arm 6, whereupon both members return to the positions illustrated, thereby again 90 positively limiting the inward movement of the armature 9, to prevent reclosure of the switch until the magnet is again energized.

What I claim as new and desire to secure by Letters Patent is:—

In an electromagnetic switch, in combination, a pivoted contact member biased toward open position, an electromagnetic winding for attracting the same to closed position, said winding having a core arranged substantially perpendicularly to said contact member with the end thereof adjacent said member projecting beyond said

winding and a pivoted lockout member located between said contact member and said winding and movable in a plane at right angles to the plane of movement of said contact member, said lockout member being biased toward a position to obstruct movement of said contact member to closed position and being attractable to the projecting end of said core to permit full movement of

said contact member to closed position upon 10 energization of said winding.

In witness whereof, I have hereunto subscribed my name in the presence of two witnesses.

CLARENCE T. EVANS.
